CLAIM

The ornamental design for a fluid cushion supported vehicle, as shown and described.

DESCRIPTION

FIG. 1 is a perspective view, (from one side and the front), of the fluid cushion supported vehicle showing our new design,

FIG. 2 is a side view of the vehicle, (other side corresponds),

FIG. 3 is a front end view of the vehicle, and

FIG. 4 is a plan view of the vehicle.

FIG.1.

FIG.2.

FIG.3.

FIG.4.
